BOTTLE CAP

George H. Hutaff, Jr., Wilmington, N. C.

Application December 29, 1938, Serial No. 248,327

6 Claims. (Cl. 215—46)

My invention relates to new and useful improvements in bottle caps and more particularly to a cap which may be applied to the mouth of a bottle or other receptacle and removed when desired without the use of the usual form of bottle cap remover or other implement.

The principal object of the invention resides in the provision of a cap of the character described including top and bottom portions adapted to be nested so that the cap may be applied to the mouth of a bottle or other receptacle as a unitary structure, the top and bottom portions being connected by a foldable or extensible member adapted to be normally positioned between the top and bottom portions but permitting the top portion to be removed from the bottom portion and to then pull the bottom portion from the mouth of the bottle or other receptacle.

Another object of the invention resides in the provision of a cap of the character described including top and bottom portions normally nested so that the cap may be applied to the mouth of a bottle or other receptacle as a unitary structure, the bottom portion being provided in turn with a weakened portion, and means normally positioned between the top and bottom portions for connecting the two portions, said connection adapting the top portion to be removed from the bottom portion and on further manipulation to tear the weakened portion from the bottom portion so that the bottom portion may be removed from the mouth of the bottle or other receptacle.

Still another object of the invention resides in the formation of a cap of the character described with top and bottom portions adapted to be normally nested so that the cap may be applied to the mouth of a bottle or other receptacle as a unitary structure, the bottom portion having a tab cut from the top thereof with weakened lines leading from the tab, and a member connected to the top portion and to the tab of the bottom portion, said connecting member permitting removal of the top portion from the bottom portion and in a manipulation of the top portion tearing the bottom portion along the weakened lines thereof.

Another object of the invention resides in the provision of a cap of the character described with nested top and bottom portions, the top and bottom portions being connected by a member normally housed between the portions but adapted to be elongated on removal of the top portion from the bottom portion.

With the above and other objects in view, which will appear as the description proceeds, my invention consists in the novel details of construction, and arrangement of parts, described in the following specification and illustrated in the accompanying drawing, and while I have illustrated and described the preferred embodiments

of the invention, as they now appear to me, it will be understood that such changes may be made as will fall within the scope of the appended claims.

In the drawing—

Fig. 1 is a top plan.

Fig. 2 is a side elevation.

Fig. 3 is a transverse vertical section.

Fig. 4 is a horizontal section on the line 4—4 of Fig. 3, looking in the direction of the arrows.

Fig. 5 is a transverse vertical section showing a slightly modified form of the invention; and

Fig. 6 is a horizontal section on the line 6—6 of Fig. 5, looking in the direction of the arrows.

As stated in the objects of the invention, the cap comprises top and bottom portions adapted to be normally nested and in the drawing the top portion is indicated generally at *a* while the bottom portion is indicated generally at *b*. Normally the portions will be nested, as shown, so that the cap may be placed upon the mouth of a bottle or other receptacle by the usual well-known form of bottle capping machine.

The top portion *a* includes the top 1, having the depending flange 2, which is slightly tapered, as shown more particularly in Fig. 3 of the drawing. The bottom portion *b* includes the top 3 and depending outwardly flared flange 4, which is corrugated or fluted in the usual manner, as shown at 5. A cork disc 6 is normally inserted into the bottom portion, as shown in Fig. 3 of the drawing. The top 3 of the bottom portion, is formed with the slit or opening 7 forming the tab 8. Leading from the ends 9 of the opening or slit 7 are the weakened lines 10, formed by perforations or indentations and these weakened lines extend horizontally across the top 3 and vertically of the flange 4.

In the form of the invention disclosed in Figs. 1 to 4 inclusive of the drawing the top and bottom portions *a* and *b* are connected by a cord or wire 11, which is normally folded or wound to be positioned between the tops of the members as is disclosed quite clearly in Figs. 3 and 4 of the drawing. The end 12, of the cord or wire, extends through an opening 13, in the flange 2 of the top member, and is bent, as shown, while the opposite end of the cord or wire is engaged through and connected to an eye 14 struck from the tab 8.

In that form of the invention disclosed in Figs. 1 to 4 inclusive of the drawing when it is desired to remove the cap from the mouth of the bottle or other receptacle the operator engages the edge of the flange 2, of the top portion *a*, and forces the same upwardly out of frictional engagement with the bottom portion *b* and when the portion *a* is thus removed it may be used as a grip for removing the bottom portion from the bottle or other receptacle. The operator pulls on the portion 1 and this, of course, extends the

wire or cord 11 and when the same becomes taut it will pull on the tab 8 and tear a strip from between the weakened lines 10 thus releasing the bottom portion from the mouth of the bottle or other receptacle. It will thus be seen that the cap may be removed by a quick pull and it is not necessary to use a bottle cap remover or other implement such as is now done. The advantages of this will be readily understood for quite often a bottle cap remover or other implement is not available or has been misplaced.

In Figs. 5 and 6 of the drawing I have shown a slightly modified form of the invention in which the top portion is indicated at *c* and the bottom portion at *d*. The top portion includes the top 15 and depending flange 16. The bottom portion *d* includes the top 17 and depending flange 18 which is corrugated or fluted in the usual manner. A cork disc 19 is inserted into the bottom portion.

A slit or opening 20 is formed in the top 17 of the bottom portion *d* and extending from the ends 21, of the slit or opening, are the weakened lines 22, formed by perforations or indentations. These weakened lines extend horizontally over the top 17 and vertically of the flange 18. The slit or opening 20 forms the tab 23, side edges of which are folded to provide the elongated eyes 24. Received in the elongated eyes 24 are the arms of a substantially C-shaped frame 25. The closed end of a substantially C-shaped frame 26 extends through an opening 27, formed in the flange, of the top member *d*, and a sleeve 28 is positioned on the horizontal portion of the frame 26 to prevent the same from being withdrawn inwardly through the opening 27. The C-shaped frames 25 and 26 are connected by the C-shaped frames 29, 30, 31 and 32. Normally these C-shaped frames will be folded into the position shown more particularly in Fig. 6 of the drawing 40 to lie between the tops 15 and 17 of the portions *c* and *d*, respectively.

Normally the portion *c* is held in position on the portion *d* by the friction between the flanges 16 and 18. When thus assembled the cap may be applied to the mouth of the bottle or other receptacle by the usual form of capping machine. When it is desired to remove the cap from the mouth of the bottle or other receptacle the operator will engage his finger beneath the bottom edge of the flange 16; of the top portion *c* and force the same upwardly. This releases the top portion *c* from the bottom portion *d* and permits the top portion *c* to be used as a finger grip. By pulling on the top portion *c* the connecting frames between the portions will be unfolded into straight line and when the same become taut a continued pull on the top portion *c* will pull the tab 23, of the bottom portion, upwardly and tear the bottom portion along the weakened lines 22. This will tear a strip from the top 17 and from the flange 18 thus releasing the bottom portion from the mouth of the bottle or other receptacle and permitting the same to be removed.

From the above detailed description it will be seen that I have provided a novel form of cap adapted to be removed without the use of a bottle cap remover or other implement. The cap is formed of top and bottom portions and when the top portion is removed a quick pull may be imparted to tear the strip from the bottom por-

tion and permit the same to be released and removed from the mouth of the bottle or other receptacle.

In a cap constructed of the two nested portions, when desired, material of somewhat less weight or thickness may be used than is the case in caps formed of only one portion or thickness.

Having fully described my invention, what I claim as new and desire to secure by Letters Patent is:

1. A cap of the character described including top and bottom members and an extensible chain-like member adapted to be normally folded to lie flat between the top and bottom members, one end of said extensible chain-like member being connected to the top member and the opposite end connected to the bottom member.

2. A cap of the character described including top and bottom portions, the top portion being formed with an opening while the bottom portion is formed with an eye, and an extensible chain-like member normally folded to lie flat and to be housed between the top and bottom portions, one end of said extensible member being passed through the opening in the top portion and connected thereto whereas the opposite end is connected in the eye of the bottom portion.

3. A cap of the character described including top and bottom portions, the bottom portion having a cut-out flap and elongated eyes formed on opposed edges, and a chain-like extensible member connecting the top and bottom portions and normally being folded to lie flat between the top and bottom portions, the extensible member including arm portions received in the elongated eyes formed on the flap of the bottom portion.

4. A cap of the character described including top and bottom portions, the top portion having an opening therein and the bottom portion having a cut-out flap with elongated eyes formed on opposed edges thereof, and a chain-like extensible member connecting the top and bottom portions and normally folded to lie flat between the top and bottom portions, one end of the extensible member extending through the opening in the top portion and held against withdrawal and the opposite end having arm portions received in the elongated eyes of the flap of the bottom portion.

5. A cap of the character described including top and bottom portions, the top portion being formed with an opening while the bottom portion is formed with an eye, and an extensible member normally housed between the top and bottom portions, one end of said extensible member being passed through the opening in the top portion and connected thereto whereas the opposite end is connected in the eye of the bottom portion.

6. A cap of the character described including top and bottom portions, the top portion having an opening therein and the bottom portion having a cut-out flap with an eye formed thereon, and an extensible member connecting the top and bottom portions and normally housed therebetween, one end of the extensible member extending through the opening in the top portion and connected thereto while the opposite end is connected in the eye of the flap of the bottom portion.
